METHOD OF SEPARATING THE COMPONENTS OF AIR

Filed July 6, 1945

UNITED STATES PATENT OFFICE

2,433,536

METHOD OF SEPARATING THE COM-
PONENTS OF AIRClaude C. Van Nuys, Greenwich, Conn., assignor
to Air Reduction Company, Incorporated, New
York, N. Y., a corporation of New York

Application July 6, 1945, Serial No. 603,555

7 Claims. (Cl. 62—175.5)

1

This invention relates to the separation of the components of the atmosphere by liquefaction and rectification and particularly to the recovery of nitrogen and the components less volatile than nitrogen in a continuous operation. Neon and helium, which are more volatile than nitrogen, are not separated. Krypton and xenon are recovered as a single fraction substantially free from nitrogen, neon and helium. Oxygen and argon are separately recovered in substantial purity.

It is the object of the invention to provide a relatively simple and effective procedure wherein air is subjected to successive operations to separate economically nitrogen, oxygen, argon and krypton-xenon free from nitrogen, neon and helium, each fraction being of commercial purity and suitable for the several uses for which they are respectively adapted.

Other objects and advantages of the invention will be apparent as it is better understood by reference to the following specification and the accompanying drawing, which illustrates diagrammatically an apparatus suitable for the practice of the invention, it being understood that details of the liquefaction system which are well known in the art are omitted in the interest of clarity.

In accordance with the invention, the air is first separated by liquefaction and rectification into two major components, a nitrogen effluent which includes the small amounts of neon and helium present in the atmosphere, and a liquid fraction consisting principally of oxygen and including argon and krypton-xenon. The liquid fraction is withdrawn and subjected to a second rectification with partial condensation of the effluent to eliminate any nitrogen which may have carried over with the liquid, to separate argon and to afford a liquid fraction including oxygen and krypton-xenon. A third rectification of this liquid eliminates the krypton-xenon as a liquid, leaving substantially pure oxygen which escapes in the gaseous phase. In order to provide refrigeration for the two auxiliary rectifications and especially to restore to the main column the liquid equivalent of the liquid lost by that column through the pipe 22a, a portion of the air entering the system is initially separated to afford an enriched oxygen liquid which is delivered in an efficient manner to the main rectifier to compensate that rectifier for its liquid loss above specified. The other portion of the air diverted to the auxiliary rectifier is uncondensed nitrogen of substantial purity. The latter is then liquefied and delivered to the condensers at the tops

2

of the auxiliary columns. The procedure as described can be conducted efficiently without re-compression of the gases. The air is initially compressed to some suitable pressure upward to 5 20 atmospheres absolute and cooled in the usual after-coolers. The successive operations thereafter are conducted at progressively lower pressures and produce continuously substantially pure nitrogen, oxygen and argon and the krypton-xenon mixture free from nitrogen, neon and helium.

Referring to the drawing, a column comprising sections 5 and 6 and an intermediate condenser section 7 is provided with trays 8 having the usual bubble caps 8a. The air from the after-coolers under suitable pressure is delivered from a pipe 9 through a flow regulating valve 10 to a pipe 11 and thence to a coil 12 in the bottom of the section 6 of the column. The air is liquefied by heat exchange with a pool of liquid which accumulates in the bottom of the column and is delivered through a pipe 13 and pressure reducing valve 14 to an intermediate level of the section 6. Flowing downwardly over the trays, the 15 liquid becomes enriched in oxygen while vapors consisting of oxygen and nitrogen rise through the tubes 15 of the condenser section 7 to a head 16. The vapors are partially condensed, the oxygen flowing backwardly into the section 6 of the column. The residue, consisting principally of nitrogen, travels downwardly through the tubes 17 in the condenser section 7, and the resulting liquid accumulates in a collector 18, whence it is delivered through a pipe 19 and pressure reducing valve 20 to the top of the section 5 of the column, thus affording the nitrogen reflux necessary to effective separation of oxygen from vapors arising through the section 5. Enriched oxygen liquid from the pool at the bottom of the 25 section 6 of the column is delivered through a pipe 21 and valve 22 to a pipe 23 and thence to an intermediate level of the section 5 of the column. As the result of rectification of the two liquids in the section 5 of the column, nitrogen 30 containing the small proportions of neon and helium present in the atmosphere escapes as an effluent through a pipe 21a at the top of the column and may be delivered through the usual exchangers (not shown) to suitable storage facilities.

The liquid which accumulates about the tubes 15 and 17 in the condenser section 7 consists principally of oxygen but contains also argon and krypton-xenon. It is delivered through a pipe 35 22a and pressure reducing valve 23a to an inter-

mediate level of a column 24 having the usual trays 25 and bubble caps 26, and flows downwardly over the trays. At the top of the auxiliary column 24, a condenser section 27 is provided with tubes 28 around which a pool of liquid nitrogen is maintained by means hereinafter described. The vapors rising through the tubes 28 are subjected to the cooling effect of the liquid nitrogen which condenses all of the vapors except any residual nitrogen which may be present. The latter escapes through a pipe 29 controlled by a valve 30 and may be delivered to storage after passing through the usual exchangers (not shown) or discharged to the atmosphere. Directly beneath the condenser 27, the vapors rising through the auxiliary column 24 consist of substantially pure argon which is withdrawn through a pipe 31 and delivered to storage. The liquid fraction which accumulates in the bottom of the auxiliary column 24 is oxygen including krypton-xenon. It surrounds a coil 32 in which nitrogen supplied as hereinafter described is liquefied and delivered through a pipe 33 and pressure reducing valve 34 to the condenser 27.

The liquid from the bottom of the auxiliary column 24 is delivered through a pipe 35 and flow regulating valve 36 to a second auxiliary column 37 having the usual trays 38 and bubble caps 39. The liquid flows downwardly over the trays into a condenser section 40 having tubes 41 and is partially vaporized. The vapors rising through the trays 38 pass upwardly through tubes 42 of a condenser section 43. The tubes are surrounded by liquid nitrogen withdrawn through an overflow pipe 44 in the condenser section 27 and delivered to the condenser section 43 through a pipe 45. Heat exchange with the cold nitrogen results in liquefaction of all but the oxygen present in the vapors. The latter escapes through a pipe 46 and after passing through the usual exchangers (not shown) may be delivered to storage. The vaporized nitrogen escapes through a pipe 47. The liquid which continuously flows downwardly over the trays 38 accumulates in the condenser section 40 and may be withdrawn from time to time through a pipe 48 controlled by a valve 49. This liquid is krypton-xenon free from nitrogen, neon and helium.

To provide the liquid nitrogen necessary for the separations accomplished in the two auxiliary columns, a portion of the entering high pressure air is withdrawn from the pipe 9 through a pipe 50 and delivered to the condenser section 40. It flows upwardly through the tubes 41 in heat exchange relation with the liquid surrounding the tube and is partially condensed. The liquid condensate is enriched oxygen liquid which is withdrawn through a pipe 51 and delivered through a pressure reducing valve 52 to the pipe 23 which conveys it with other enriched oxygen liquid into the section 5 of the primary column. The residue of the gas in the tubes 41 consists principally of nitrogen which is withdrawn through the pipe 53 and delivered to the coil 32 where it is liquefied as hereinbefore described, thus affording the liquid refrigerating agent for the two auxiliary columns.

The procedure as described may be conducted at any suitable pressures sufficient to ensure satisfactory operation. Thus, if the initial pressure is upward to 20 atmospheres, the pressure in the section 6 of the primary column may be approximately 5 atmospheres absolute, and the pressure in the section 5 of the primary rectifier may be approximately 1 atmosphere absolute.

The columns 24 and 37 will then be operated at fractions of an atmosphere below that maintained in the section 5 of the primary column. These pressures are, however, merely illustrative of suitable operation and may be varied without substantially modifying the results obtained.

The procedure affords large volumes of relatively pure nitrogen. It can produce oxygen of any desired purity as for example from 95 to 10 99.6%, and both argon and krypton-xenon substantially free from nitrogen, neon and helium. As indicated, any nitrogen which may be carried over from the primary column is eliminated in the first auxiliary column and hence cannot 15 contaminate the argon, oxygen and krypton-xenon which are separated from the remaining liquid.

Various changes may be made in the details of procedure as described without departing from 20 the invention or sacrificing the advantages thereof.

I claim:

1. The method of recovering continuously from the atmosphere, nitrogen, oxygen, argon and krypton-xenon which comprises, initially separating air by liquefaction and rectification into a gaseous fraction consisting of a part of the nitrogen and air components more volatile than nitrogen and a liquid fraction consisting of the 25 remaining components of air, separating nitrogen and argon respectively from the liquid fraction by rectification followed by partial condensation of the effluent vapors from the rectification, and subjecting the residual liquid product of the second rectification to further rectification followed by partial condensation of the effluent vapors from such further rectification to release oxygen in the vapor phase and to recover a liquid 30 consisting essentially of krypton-xenon free from nitrogen, neon and helium.

2. The method of recovering continuously from the atmosphere, nitrogen, oxygen, argon and krypton-xenon which comprises, initially separating air by liquefaction and rectification into a gaseous fraction consisting of a part of the nitrogen and air components more volatile than nitrogen and a liquid fraction consisting of the 35 remaining components of air, separating nitrogen and argon respectively from the liquid fraction by rectification followed by partial condensation of the effluent vapors from the rectification by indirect heat exchange with liquid nitrogen, and subjecting the residual liquid product of the second rectification to further rectification followed by partial condensation of the effluent vapors from such further rectification to release oxygen in the vapor phase and to recover a liquid 40 consisting essentially of krypton-xenon free from nitrogen, neon and helium.

3. The method of recovering continuously from the atmosphere, nitrogen, oxygen, argon and krypton-xenon which comprises, initially separating air by liquefaction and rectification into a gaseous fraction consisting of a part of the 45 nitrogen and air components more volatile than nitrogen and a liquid fraction consisting of the remaining components of air, separating nitrogen and argon respectively from the liquid fraction by rectification followed by partial condensation of the effluent vapors from the rectification by indirect heat exchange with liquid nitrogen, subjecting the residual liquid to further rectification followed by partial condensation of the effluent vapors from such 50 further rectification to release oxygen in the

vapor phase and to recover a liquid consisting essentially of krypton-xenon free from nitrogen, neon and helium, and providing the liquid nitrogen by partial condensation of a portion of the air undergoing treatment and condensation of the residual nitrogen.

4. The method of recovering continuously from the atmosphere, nitrogen, oxygen, argon and krypton-xenon which comprises, initially separating air by liquefaction and rectification into a gaseous fraction consisting of a part of the nitrogen and air components more volatile than nitrogen and a liquid fraction consisting of the remaining components of air, separating nitrogen and argon respectively from the liquid fraction by rectification followed by partial condensation of the effluent vapors from the rectification by indirect heat exchange with liquid nitrogen, subjecting the residual liquid to further rectification followed by partial condensation of the effluent vapors from such further rectification by indirect heat exchange relation with liquid nitrogen to release oxygen in the vapor phase and to recover a liquid consisting essentially of krypton-xenon free from nitrogen, neon and helium, and providing the liquid nitrogen by directing a portion of the air undergoing separation in indirect heat exchange with the krypton-xenon liquid to effect partial condensation of the air and conducting the uncondensed residue in indirect heat exchange with the liquid oxygen fraction.

5. The method of recovering continuously from the atmosphere, nitrogen, oxygen, argon and krypton-xenon which comprises, initially separating air by liquefaction and rectification into a gaseous fraction consisting of a part of the nitrogen and air components more volatile than nitrogen and a liquid fraction consisting of the remaining components of air, separating nitrogen and argon respectively from the liquid fraction by rectification followed by partial condensation of the effluent vapors from the rectification by indirect heat exchange with liquid nitrogen, and subjecting the residual liquid to further rectification followed by partial condensation of the effluent vapors from such further rectification by indirect heat exchange with liquid nitrogen to release oxygen in the vapor phase and to recover a liquid consisting essentially of krypton-xenon free from nitrogen, neon and helium.

6. The method of recovering continuously from the atmosphere, nitrogen, oxygen, argon and krypton-xenon which comprises, initially separating air by liquefaction and rectification into a gaseous fraction consisting of a part of the nitrogen and air components more volatile than nitrogen and a liquid fraction consisting

of the remaining components of air, separating nitrogen and argon respectively from the liquid fraction by rectification followed by partial condensation of the effluent vapors from the rectification by indirect heat exchange with liquid nitrogen, subjecting the residual liquid to further rectification followed by partial condensation of the effluent vapors from such further rectification by indirect heat exchange relation with liquid nitrogen to release oxygen in the vapor phase and to recover a liquid consisting essentially of krypton-xenon free from nitrogen, neon and helium, and providing the liquid nitrogen by partial condensation of a portion of the air undergoing treatment and condensation of the residual nitrogen.

7. The method of recovering continuously from the atmosphere, nitrogen, oxygen, argon and krypton-xenon which comprises, initially separating air by liquefaction and rectification into a gaseous fraction consisting of a part of the nitrogen and air components more volatile than nitrogen and a liquid fraction consisting of the remaining components of air, separating nitrogen and argon respectively from the liquid fraction by rectification followed by partial condensation of the effluent vapors from the rectification by indirect heat exchange with liquid nitrogen, subjecting the residual liquid to further rectification followed by partial condensation of the effluent vapors from such further rectification by indirect heat exchange relation with liquid nitrogen to release oxygen in the vapor phase and to recover a liquid consisting essentially of krypton-xenon free from nitrogen, neon and helium, and providing the liquid nitrogen by directing a portion of the air undergoing separation in indirect heat exchange with the krypton-xenon liquid to effect partial condensation of the air and conducting the uncondensed residue in indirect heat exchange with the liquid oxygen fraction.
